Attorney

UNITED STATES PATENT OFFICE.

EDWARD BRADLEY, OF OGDEN, ILLINOIS.

PIPE WRENCH.

Application filed November 18, 1921. Serial No. 516,158.

To all whom it may concern:

Be it known that I, EDWARD BRADLEY, citizen of the United States, residing at Ogden, in the county of Champaign and State 5 of Illinois, have invented certain new and useful Improvements in Pipe Wrenches, of which the following is a specification.

The invention relates to pipe wrenches and more particularly to a pipe wrench having gripping jaws designed to grip the work 10 without slipping.

The main object of the invention is to provide a wrench of light weight and suitable construction enabling it to be conveniently used in small and cramped places, the gripping jaws being so disposed relative to the handle of the device as to enable the latter to be readily manipulated.

A further object of the invention is to 20 provide a device of the above character that is simple in construction, strong and durable and which it is believed may be manufactured at a reasonably low cost.

Various other objects and advantages of 25 the invention will become apparent during the continuance of the following description.

In the drawings:—

Figure 1 is a side elevation of a wrench 30 constructed in accordance with the invention.

Figure 2 is a top plan view of the wrench.

Figure 3 is a view in side elevation showing the wrench in operative relation to a 35 piece of pipe or other work.

In the drawings, 10 designates the handle of the wrench which is enlarged and thickened at the jaw ends as indicated at 11, from which thickened portion projects the rigid 40 jaw member 12.

At the outer end where the rigid jaw and handle meet, the latter is provided with a 45 shouldered portion formed by cut-outs on opposite sides of a centrally projecting tongue 13, the cut-outs being indicated respectively at 14 and 15 and serving to provide sockets for the circular bearing ends 16 and 17 respectively of the outer or movable wrench jaw 18. This jaw is connected to tongue 13 of the handle by means of a 50 pivot pin 19 which may be headed at each end to prevent separation of the parts.

The stationary or rigid jaw 12 is somewhat cam shaped in design, being provided with a gripping edge 20 projecting forwardly of the shouldered portion of the handle in a circular arch as shown to advantage in Figure 1 of the drawings. The movable jaw 18 of the wrench is arched to engage over the rigid jaw and is such length that when the jaws are fully closed the point or extremity 21 of the movable jaw extends beyond the outer end of the rigid jaw, providing a lip useful for obtaining a purchase on pipes before the jaws are fully opened. The inner or working edge of the outer jaw is curved to conform to the curvature of the cam shaped inner jaw and the working edges of both jaws may be suitably recessed or grooved transversely to provide the necessary jaw teeth. 70

From the dotted line construction of Figure 1 it will be noted that the movable jaw is permitted to swing outwardly from the rigid jaw until its shank is substantially at right angles to the handle, the outward adjustment of the movable jaw being limited only by the rear walls of cut-outs 14 and 15. Consequently, pipes of varying sizes may be engaged between the jaws of this wrench and the cam edge of the lower jaw will tend to bind the pipe more securely between the jaws as the handle is forced downwardly for turning the wrench. Furthermore, the provision of the recesses at the end of the handle enables the movable jaw to be pivoted thereto 75 inwardly of the upper edge of the handle, thereby avoiding any projection beyond the latter and permitting the two jaws to more snugly engage each other. 85

From the foregoing it is believed that the 90 advantages and novel features of the invention will be readily understood and therefore further detailed description is deemed unnecessary.

What is claimed is:—

A pipe wrench comprising a handle having a relatively thickened portion at one end provided with an integral extension disposed below the plane of the handle to present a rigid jaw, said handle being cut out at a 100 place along the upper edge where the handle and jaw meet to provide a centrally pro-

jecting tongue and circular sockets on opposite sides of the tongue, the said rigid jaw being cam shaped and provided with a gripping face extending forwardly of the cut out in the arc of a circle, and a movable jaw pivotally engaged with the said central tongue of the cut out and having circular bearing ends engaging in the said sockets,

the said movable jaw being arched to engage over the gripping face of the rigid jaw and being of such length that when the jaws are fully closed the end of the movable jaw extends over beyond the end of the rigid jaw, providing a lip for a useful purpose.

In testimony whereof I affix my signature.
EDWARD BRADLEY.
